UNITED STATES PATENT OFFICE.

GEORGE RAMSEY, OF BROOKLYN, NEW YORK, ASSIGNOR; BY MESNE ASSIGNMENTS, TO STEWART WARNER SPEEDOMETER CORPORATION, A CORPORATION OF VIRGINIA.

LIQUID-FUEL FEED.

Application filed December 21, 1921, Serial No. 524,003. Renewed July 16, 1925.

To all whom it may concern:

Be it known that I, GEORGE RAMSEY, a citizen of the United States, residing in Brooklyn, in the county of Kings, State of New York, have invented certain new and useful Improvements in Liquid-Fuel Feed, of which the following is a specification.

The present invention relates broadly to liquid fuel feeds and more specially to a vacuum fuel feeding system for hydrocarbon engines and the like.

There are three different types of vacuum fuel feeds recognized in the art; namely, the intermittently open system, the closed system, and the constantly open system. These systems are described more specially with reference to the condition of the vacuum tank.

The present invention relates more specially to the constantly open type. In the constantly open type there is a vent which is maintained constantly open and which continually admits air to the vacuum chamber. In order to maintain a partial vacuum sufficient to draw gasoline from a main tank while atmosphere is entering through the vent, constructions are necessitated which permit the relatively quick withdrawal of the air from the vacuum chamber when the suction valve is open. It is necessary that the float for operating the suction valve shall be heavy enough to open the suction valve after the contents of the vacuum chamber have drained into the storage chamber and at the same time the buoyancy of the float must be sufficient to enable the float to rise as rapidly as the gasoline rises in the vacuum chamber when suction is effective so that the suction valve is closed before the vacuum chamber is over-filled. These conditions impose limitations on the open system constructions which make it desirable to have a relatively large suction conduit which should not be restricted, which consequently makes it desirable that the valve opening shall be large. Large valve openings increase the area effected by suction when the valve is closed thereby necessitating increasing the weight of the float to withdraw the valve from the seat when the valve is to be opened. Heretofore in the art various ex-

pedients have been adopted to meet these conditions and such expedients have complicated the valve structure so that it has either been complex mechanically or expensive to build.

The present invention overcomes the difficulties of the known art by providing a suction valve of simple construction adapted to be operated by a buoyant float and to have a valve opening of relatively large area so that the vacuum conduit is not restricted. This may be accomplished by providing a pair of valves one of which is of relatively small area and adapted to introduce air into the vacuum line before the larger valve is removed from its seat. The introduction of air into the vacuum line decreases the effective suction on the large valve and permits the large valve to be more easily withdrawn from its valve seat. As a matter of convenience the two valves may be associated so that the larger valve carries the smaller valve. It is desirable that the float shall be suspended when it reaches its lower limit of travel and the construction sustaining the larger valve may comprise an arrangement whereby the valve stem for the smaller valve may carry a bridge adapted to rest on the larger valve so that the larger valve structure becomes the sustaining member for the stem of the small valve which carries the float.

Heretofore in the art it has been customary merely to provide flap valves of various constructions to comprise the dump valve used to seal the conduit between the vacuum chamber and the storage chamber. This dump valve must seal tightly otherwise leakage will cause the liquor in the storage tank to be drawn back into the vacuum chamber if the valve is immersed, and if the dump valve is not immersed then air will be drawn through the leaky dump valve. It therefore has been the custom to make dump valves relatively small since a small valve seat is more easily made air-tight than a large one. Small dump valves, however, restrict the flow of fuel from the vacuum tank to the storage tank. An important factor in the volume of fuel pumped by a vacuum tank system is the rapidity with

which the vacuum chamber dumps or empties. It is, therefore, desirable to provide constructions which will quickly empty the vacuum tank.

6 The present invention also overcomes the difficulties of the prior art as to the dump valve in that it provides a construction having the walls thereof constructed along stream-line contours, thereby obviating any 10 retarding action due to eddies etc., and the valve disk itself is shaped to continue the stream line structure so that the conduit leading to the dump valve and the disc valve itself are so arranged as to greatly facilitate 15 discharge of the vacuum tank.

Having generally described the invention it may be stated that the principal object thereof is a vacuum fuel system comprising a plurality of valves for the suction line, 20 and with said valves adapted to be successively operated.

Another object of the present invention is a control valve for the suction line of a 25 vacuum tank fuel system so constructed as to comprise axially arranged members adapted to suspend a valve operating float when the valves are open.

Another object of the present invention is a valve for vacuum tanks or the like comprising a valve control for the vacuum line 30 and having a large opening and a small opening with constructions arranged to open and close the small opening prior to the opening and closing of the large opening.

35 A still further object of the present invention is a double valve for the suction line of a vacuum tank, said double valve comprising a small valve to admit air to the suction line before the large valve is removed from its valve seat.

Another primary object of the present invention is to provide a dump valve for 40 vacuum tanks and the like with the valve conduit constructed to comprise a stream line opening to obviate eddies in the liquid flowing from the vacuum tank.

Another object of the present invention is a dump valve for vacuum tanks or the like comprising a stream line conduit closed by a 45 coniform disk the walls of which are stream line in shape.

Other and further objects of the present invention will in part be obvious and will 50 in part be pointed out hereinafter in the specification following by reference to the accompanying drawings throughout which like characters are used to represent like parts.

Realizing that the present invention may 55 be embodied in constructions other than those herein specifically shown and described, it is desired that the disclosure herewith shall be considered as illustrative and not in the limiting sense.

60 Figure 1 is a sectional view through a

vacuum tank comprising one embodiment of the present invention.

Figure 2 is a detail illustrating the large valve closed and the small valve open;

Figure 3 is a view illustrating both valves 70 open;

Figure 4 is a sectional detail view showing the dump valve disassembled;

Figure 5 is more or less a diagrammatical 75 view illustrating the connection with a vacuum tank with a supply reservoir and a hydrocarbon engine.

Referring now to the drawings, the storage chamber 1 is provided with suitable fastening members 2 by which the tank may be 80 attached as desired adjacent a hydrocarbon engine or the like. This storage chamber is provided with an outlet 4 adapted to lead gasoline or the like to the place of use, for example, a carburetor 5 of a hydrocarbon 85 engine 6. The storage chamber is vented to atmosphere by a vent pipe 7 which may be curved downwardly to prevent dust and dirt from entering the storage chamber. A suitable neck 8 may be provided on the storage chamber and preferably is arranged with a collar 9 on the upper end. This collar 95 constitutes a support on which the vacuum chamber 10 may rest and over which the cover 11 may be secured by suitable machine screws or the like. The vacuum chamber preferably is a relatively long cylindrical vessel provided on its lower end with a dump valve 12 which may comprise a flanged section 14 screw threaded on its exterior and adapted to receive a nut 15 provided with arms 16 which form guides and stops for the valve disk 17. This valve disk is constructed to seat on a valve seat formed 100 on the end of the flanged member 14 and the valve disk is coniform with the sides thereof 105 curved in stream-line formation. The opening 18 in the flanged section is likewise of stream-line formation, thereby obviating eddies when the dump valve is opened and thus permitting the contents of the vacuum chamber 10 to quickly empty into the storage chamber 1. This is of considerable 110 importance in view of the fact that one factor in the capacity of operation of the tank is the rapidity with which the vacuum chamber may be emptied.

The cover 11 of the vacuum tank comprises a member provided with a screen well 19 from which a connection 20 leads to the main tank 21, which main tank is vented to atmosphere so that no vacuum is formed in the main tank as the liquid fuel is withdrawn. The cover also carries a connection 22 adapted to be connected to intake manifold of the hydrocarbon engine 6 so that when the engine is operating a partial vacuum will be formed in the conduit. The vacuum may be obtained by any other means, but the manifold connection affords a 115 120 125 130

convenient way of obtaining the necessary vacuum. The inner end of the connection may comprise a member 24 which is provided on its lower end with screw threads 25 that carry a nut 26 provided with arms 27 that form the support for a disk valve 28. This disk valve is of relatively large size and is adapted to seat against a valve seat 29 on the end of the member 24. A valve stem 30 may extend through the disk valve and upwardly through a guide opening 31 formed in the member 24 with the upper end of the guiding opening capped by a cap nut 32. The valve stem preferably is provided with a bridge stop 34 above the disk valve and with a spherical or conical valve 35 below the disk valve. This spherical valve 35 is adapted to seat on a valve seat 36 formed in the disk. The valve construction just described is intended to comprise a two-valve arrangement, which for convenience is illustrated as being in one structure. This two valve arrangement is intended to permit air to be introduced into the conduit 37 through a small valve before the large valve 35 is to be opened. This reduces the amount of suction in the conduit 37 and permits the large valve to be more easily withdrawn. The air which is supplied through the small valve 35 enters the vacuum chamber through the constantly open vent 38. The valve stem at its lower end is provided with an L-shaped extension 39 which forms an interlock by extending through the bracket 40 on the float 41. Preferably a small coiled spring 42 is provided above the bracket 30 so that the coil spring gently closes the valves and prevents any pounding of the valves due to the rising of the float and the jarring of the parts where the invention is used in an automobile that is being run over relatively rough roads. From this construction it will be noted that the area of the vacuum conduit 37 is relatively large and is not reduced at the valve opening. This facilitates full effect being given to the suction which causes the vacuum chamber to rapidly fill with fuel drawn from the main supply.

Assuming the valves 28 and 35 to be open and that the hydrocarbon engine is started, the air from the vacuum chamber 10 is rapidly withdrawn through the conduit 37 since this conduit is relatively large and the valve opening is also large. The air in the vacuum chamber is withdrawn much more rapidly than air comes in through the vent 38 so that a partial vacuum is quickly formed in the vacuum chamber. This immediately seats the dump valve 12, and causes liquid fuel to be raised from the main storage tank 21 to the vacuum chamber 10. As the liquid fuel fills this chamber the float 41 rises until the cushion spring 42 engages the spherical valve 35 and lifts this valve against its seat in the disk valve 28 after which both valves are lifted until suction in the suction line snaps the disk valve tightly against the valve seat 29. Suction in the suction conduit holds both valves 28 and 35 against their respective valve seats and completely cuts off suction from the vacuum chamber. Air continuing to come into the vacuum chamber through the open vent 38 relieves the partial vacuum in the vacuum chamber so that the force of gravity opens the dump valve and the liquid in the vacuum chamber quickly flows through the stream-line conduit into the storage chamber 1 and from there to the place of use. After the liquid in the vacuum chamber has lowered sufficiently to cause the bracket 40 on the float 41 to engage the hook 39 on the valve stem 36 a further lowering of the liquid level causes the weight of the float to exert a pull tending to unseat the spherical valve 35. Since the area of this valve seat is small this valve is quickly opened and air in the vacuum chamber rushes into the conduit 37 and reduces the vacuum therein so that the large valve 28 is quickly unseated by the bridge stop 34. The arms 27 catch the disk 28 and the bridge stop 34 sustains the valve stem which now suspends the float. A cycle of operations has now been completed and a new cycle begins with the closing of the dump valve.

The constructions described are such as may largely be made by automatic machinery and are very easily assembled, as well as being sturdy and mechanically simple, and highly efficient in operation. This efficient action is particularly noticeable with reference to the absence of raw fuel being drawn into the manifold. It will be noted that the conduit 37 comprises a large vertical bore through which the stem 30 extends and a smaller horizontal bore which is adapted to be connected with the suction line 22. The large disk valve 28 when resting upon the lower ends of the arms 27 is spaced a relatively large distance from the valve seat 29 and thus a relatively large space is provided for the flow of out going air over the disk and into the vertical conduit. The larger the outlet space, the lower the velocity of the air particles being withdrawn by suction. These air particles do not reach a high velocity until the conduit becomes constricted as at the horizontal portion of the bore 37. This is far above the raw gasoline and the low velocity air at the inlet over the large valve does not lift the raw liquid. Where small suction valves are used, as has been common in the art, the high rate of air travel through the small valve carries with it all spray, beads, or drops of gasoline that are in the vicinity of the valve. Such action of small valves causes this raw fuel to be drawn into the engine in its raw state

thereby producing many motor troubles, such as carbon deposits, thinning of lubrication and bad fuel mixtures. All these difficulties are overcome by the valve construction of the present invention.

Having thus described my invention, what I claim is:

1. In a vacuum fuel feeding system, the combination of a storage chamber, a vacuum chamber, means to produce suction, a vacuum conduit located above the liquid level in the vacuum chamber and operatively connecting said means with the vacuum chamber, and a pair of valves controlling the effect of the suction on said vacuum chamber said valves comprising a large valve and a small valve, both of said valves controlling openings from the vacuum chamber leading to the vacuum conduit, and means for opening and closing the small valve prior to the opening and closing of the large valve.
2. In a vacuum fuel feeding system, the combination of a main tank, a storage chamber, a vacuum chamber operatively connected to the main tank, means to produce suction, a vacuum conduit located above the liquid level in the vacuum chamber and operatively connecting said means with the vacuum chamber, and a pair of valves controlling the effect of the suction on said vacuum chamber said valves comprising a large valve and a small valve, both of said valves controlling openings from the vacuum chamber leading to the vacuum conduit, and a float in the vacuum chamber for opening and closing the small valve prior to the opening and closing of the large valve.
3. In a vacuum fuel feeding system, the combination of a storage chamber, a vacuum chamber, means to produce suction, a vacuum conduit located above the liquid level in the vacuum chamber and operatively connecting said means with the vacuum chamber, and a plurality of valves controlling the effect of the suction on said vacuum chamber said valves comprising valves graduated in size, said valves controlling openings from the vacuum chamber leading to the vacuum conduit, and means for opening and closing the smallest valve prior to the opening and closing of the largest valve.
4. In a vacuum fuel feeding system, the combination of a storage chamber, a vacuum chamber, means to produce suction a vacuum conduit located above the liquid level in the vacuum chamber and operatively connecting said means with the vacuum chamber, and a pair of valves controlling the effect of the suction on said vacuum chamber said valves comprising a large valve and a small valve, both of said valves controlling openings from the vacuum chamber leading to the vacuum conduit, and means for opening

and closing the small valve prior to the opening and closing of the large valve, said large valve carrying the small valve.

5. In a vacuum tank system for supplying liquid fuel to hydrocarbon engines or the like, the combination of a storage chamber, a vacuum chamber, a dump valve between said vacuum chamber and said storage chamber, said dump valve comprising a conduit having the side walls thereof formed of stream-line contours, a valve seat on the end of said conduit, and a coniform disk adapted to seat upon said valve seat.

6. In a vacuum tank system for supplying liquid fuel to hydrocarbon engines or the like, the combination of a main tank, a storage chamber, a vacuum chamber operatively connected to the main tank, a dump valve between said vacuum chamber and said storage chamber, said dump valve comprising a conduit having the side walls thereof formed of stream-line contours, a valve seat on the end of said conduit, and a coniform disk adapted to seat upon said valve seat.

7. In a vacuum tank system for supplying liquid fuel to hydrocarbon engines or the like, the combination of a storage chamber, a vacuum chamber, a dump valve between said vacuum chamber and said storage chamber, said dump valve comprising a conduit having the side walls thereof formed of stream-line contours, a valve seat on the end of said conduit, and a coniform stream-line disk adapted to seat upon said valve seat, and to form a stream-line opening over the disk when the valve is open.

8. In a vacuum tank system for supplying liquid fuel to hydrocarbon engines or the like, the combination of a storage chamber, a vacuum chamber, a dump valve between said vacuum chamber and said storage chamber, said dump valve comprising a conduit, a valve seat on the end of said conduit, a coniform disk adapted to seat upon said valve seat, and an open spider support for said disk.

9. In a vacuum tank system for supplying liquid fuel to hydrocarbon engines or the like, the combination of a main tank, a storage chamber, a vacuum chamber operatively connected to the main tank, a dump valve between said vacuum chamber and said storage chamber, said dump valve comprising a conduit, a valve seat on the end of said conduit, and a coniform stream-line disk adapted to seat upon said valve seat, and to form a stream-line opening over the disk when the valve is open.

10. In a vacuum fuel feed system, a float controlled suction valve; said suction valve comprising a large disk member, a small valve seat on said disk member, a valve stem extending through said disk member, a small valve carried by said valve stem,

and a stop on said valve stem; in combination with a conduit provided with a valve seat for said disk valve; means to support said disk valve when the same is removed from the valve seat whereby said disk valve is adapted to sustain said valve stem; a float; a connection between said float and said valve stem whereby a telescopic action is permitted between said valve stem and said float and to cause said float to be suspended by said valve stem when the float reaches the lower limit of travel.

11. In a vacuum fuel feed system, a float controlled suction valve; said suction valve comprising a large disk member, a small valve seat on said disk member a valve stem extending through said disk member, a small valve carried by said valve stem, and a bridge stop on said valve stem and above said disk member, in combination with a conduit provided with a valve seat for said disk valve; means to support said disk valve when the same is removed from the valve seat whereby said disk valve is adapted to sustain said valve stem; a float; a connection between said float and said valve stem whereby a telescopic action is permitted between said valve stem and said float and to cause said float to be suspended by said valve stem when the float reaches the lower limit of travel.

12. In a vacuum fuel feed system, a float controlled suction valve; said suction valve comprising a large disk member, a small valve seat on said disk member, a valve stem extending through said disk member, a small valve carried by said valve stem, and a stop on said valve stem; in combination with a conduit provided with a valve seat for said disk valve; a guide for said valve stem, means to support said disk valve when the same is removed from the valve seat whereby said disk valve is adapted to sustain said valve stem; a float, a connection between said float and said valve stem whereby a telescopic action is permitted between said valve stem and said float and to cause said float to be suspended by said valve stem when the float reaches the lower limit of travel.

13. In a vacuum fuel feed system, a float controlled suction valve; said suction valve comprising a large disk member, a small valve seat on said disk member, a valve stem extending through said disk member, a small valve carried by said valve stem, and a stop on said valve stem; in combination with a conduit provided with a valve seat for said disk valve; means comprising supporting arms to support said disk valve when the same is removed from the valve seat whereby said disk valve is adapted to sustain said valve stem; a float; a sliding connection between said float and said valve stem whereby a telescopic action is permitted between said valve

stem and said float and to cause said float to be suspended by the stop resting upon the disk member and supporting said valve stem when the float reaches the lower limit of travel.

14. In a vacuum fuel feed system, a vacuum chamber, a suction conduit leading to said vacuum chamber, a valve seat on the end of said suction conduit, a float operated valve adapted to control said conduit, a float, a valve stem movable through said valve and operatively connecting said float with said valve to cause said valve to support said stem and suspend said float when the valve is open and the float is at the lower limit of its travel.

15. In a vacuum fuel feed system, a main tank, a vacuum chamber operatively connected with the main tank, a suction conduit leading to said vacuum chamber, a valve seat on the end of said suction conduit, a float operated valve adapted to control said conduit, a float, and a valve stem operatively connecting said float with said valve to cause said valve to support said stem and suspend said float when the valve is open and the float is at the lower limit of its travel.

16. In a vacuum fuel feed system, a vacuum chamber, a suction conduit, leading to said vacuum chamber, a valve seat on the end of said suction conduit, a float operated valve adapted to control said conduit, a nut provided with a plurality of arms to support said valve, a float, means operatively connecting said float with said valve to cause said valve to suspend said float when the valve is open and the float is at the lower limit of its travel.

17. In a vacuum tank fuel feed system, the combination of a vacuum chamber, a storage chamber, a suction conduit leading to said vacuum chamber, a double valve for controlling said suction conduit, means for opening and closing said valves successively, a storage chamber, a dump valve between said vacuum chamber and said storage chamber, said dump valve being provided with a stream-line opening through which fuel from said vacuum chamber may quickly flow to said storage chamber.

18. In a vacuum tank fuel feed system, the combination of a vacuum chamber, a storage chamber, a suction conduit leading to said vacuum chamber, a multiple valve for controlling said suction conduit, float means for opening and closing said valve successively to render the suction gradually effective upon the vacuum chamber, a storage chamber, a dump valve between said vacuum chamber and said storage chamber, said dump valve being provided with a stream-line opening through which fuel from said vacuum chamber may quickly flow to said storage chamber.

GEORGE RAMSEY.
